William D. Ross,

UNITED STATES PATENT OFFICE.

WILLIAM D. ROSS, OF WINNIPEG, MANITOBA, CANADA.

COLLAR-SECURING MEANS.

1,331,725.

Specification of Letters Patent. Patented Feb. 24, 1920.

Application filed February 14, 1918. Serial No. 217,089.

To all whom it may concern:

Be it known that I, WILLIAM D. Ross, a subject of the King of England, residing at Winnipeg, in the Province of Manitoba and 5 Dominion of Canada, have invented certain new and useful Improvements in Collar-Securing Means, of which the following is a specification.

This invention relates to collar securing 10 means, and more particularly to means for securing a collar to the shirt neck band.

One of the main objects of the invention is to provide a securing means of the character stated of simple construction and operation 15 which is carried by a collar and permanently secured thereto so as to avoid danger of loss of any of the elements of the device. A further object is to provide a securing means of simple construction and neat appearance 20 which may be readily applied to collars of standard construction. Another object is to provide a securing means by means of which the collar may be readily detachably secured to the neck band of a shirt. Further objects will appear from the detailed description.

In the drawings:

Figure 1 is a front perspective view of a collar with a securing means constructed in 30 accordance with my invention,

Fig. 2 is a section taken substantially on line 2—2 of Fig. 1,

Fig. 3 is a section taken substantially on line 3—3 of Fig. 1.

The collar A is of standard construction 35 being provided with the inner fold b and the outer fold c. A tab 1 of fabric is secured at its upper end, by sewing or in any other suitable manner, to the inner face of inner fold b at the center at the back of the 40 collar. The tab is provided, in its lower end, with a stud 2 so positioned that the shank thereof may be inserted through the usual opening in the back of the neck band 3, and, 45 the corresponding opening through the inner fold b of the collar. The head 4 formed on the outer end of shank 2^a is adapted to be received into a socket 5 which is secured in the inner fold of the collar with the recess 50 which receives the head 4 coincident with the opening through which the head is inserted.

By inserting shank 2^a through the neck band 3 and then pressing the two members of the securing device together so as to force the head 4 into socket 5, the inner fold b of the 55 collar is firmly but releasably secured to neck band 3 at the back thereof. A similar tab 1^a is secured to the inner face of inner fold b of the collar adjacent one end thereof, and carries a socket 5^a which is adapted to receive a head 4^a formed at the inner end of the shank 2^a of a stud 2^b carried by one of the overlapping end portions b' of the fold b of collar A, the shank 2^a being inserted through the usual opening 6 in the overlapping end portion of the neck band 3 at the front end thereof. By means of the stud and socket fastener illustrated, the collar may be readily secured to the neck band of a shirt, and all danger of loss of any of the securing 70 elements is eliminated. When it is desired to remove the collar, this may be readily accomplished by detaching the members of the fasteners thus permitting the collar to be taken from the neck band. In practice, the 75 elements of the fasteners may be formed in the usual manner and secured to the tabs and the collar by pressing so as to be firmly fastened thereto and to occupy but very little space. As a securing means of this sort may 80 be produced at very small cost, the fasteners may be readily applied to collars of standard construction without any material increase in the cost of the same.

What I claim is:

A collar of the type comprising inner and outer folds, and having the ends of the inner fold extended, a tab secured at its upper end centrally of the inner face of the inner fold, a headed stud at the lower end of the 90 tab, a socket at the lower edge of the inner fold to receive the said stud, a headed stud at one of the extended ends, a tab attached to the other extended end, and a socket carried by the free end of the last mentioned 95 tab to receive the stud of the extended end.

In testimony whereof I affix my signature in presence of two witnesses.

WILLIAM D. ROSS.
